UNITED STATES PATENT OFFICE.

ARTHUR TAPPAN BECKER, OF COHOES, NEW YORK.

IMPROVEMENT IN POCKET-FLASKS.

Specification forming part of Letters Patent No. 99,051, dated January 25, 1870.

To all whom it may concern:

Be it known that I, ARTHUR TAPPAN BECKER, of Cohoes, in the county of Albany and State of New York, have invented a certain new and useful Improvement in Pocket-Flasks, of which the following is a full, clear, and exact description.

It is the object of my invention to so construct a top for a pocket-flask in two parts or sections that the turning of a section in one direction shall bring an opening therein over a corresponding opening in the other section, to allow the liquid contained in the flask to run out, or be drawn up by applying the lips to a mouth-piece secured in the opening of the upper section, and the turning of the section the other way shall stop the flow of liquid and prevent leakage by a suitable packing between the two sections; and the improvement herein claimed consists in the combination, with a flask or bottle top formed in two parts, one part turning upon the other, of two openings in each section, (one opening in each section, when arranged one directly above the other, being for the admission of air to the flask or bottle, and the other two openings, when brought one immediately over the other, being for the passage of the liquid from the flask or bottle,) a packing between the sections, a mouth-piece, and a tube communicating with the mouth-piece and extending down into the flask or bottle.

In the accompanying drawings, Figure 1 represents a view in perspective of a flask with my improved top adapted thereto, and Fig. 2 a vertical central section through the same.

A represents a pocket-flask (in this instance of glass with a protecting-cover) having suitably secured upon its neck a metallic band or clasping-ring, *a*, with a screw formed upon its outside. The top is formed in two parts, *Bb*, a flange, *b'*, on the part *B* fitting snugly upon the recessed sides of the part *b*, which is provided with a screw-flange, *b²*, and secured upon the threaded neck-ring *a*. The flange *b'* of the upper section of the top, and the screw-flange *b²* of the lower section, *b*, respectively rest a little above or upon shoulders formed upon the lower section of the top and the neck-ring. Around the edges of the under side of the top of the part *b* is secured a packing-ring, *c*, in this instance of leather, which fits and presses upon the top of the neck-ring *a*, to prevent leakage. To the under side of the part *B* is secured a

packing, *c'*, of the same material as that *c* of the part *b*, but extending across the under side of the top of the part *B*, (instead of being secured at its edges only,) and fitting around the central stud or projection, *d*, upon the part *b*. Two holes, *e e*, are made in the top of the lower part or section, *b*, of the top, and two holes, *e' e'*, are made in the top of the part *B* and in the packing *c'*. These holes in each section are made at equal distances from the centers of the parts *Bb* of the top, and so that those in one section will register with those in the other section when the top section is turned to the proper position upon its pivot *f*, as shown in Fig. 1. This pivot *f* is formed with a thread upon its lower end, to screw into the short stud *d* on top of the lower section, *b*, of the top, and serves also as a set-screw to regulate the extent of pressure upon the packing *c'*, so that either thick or thin or hard or soft material may be used for packing, and when it becomes worn by use the screw-pivot *f* serves to render it still capable of being used by pressing down the section *B* upon the section *b*. The turning movement of one section upon the other, to open or shut off the passage for the liquid from the flask by one set of holes, and the passage for air to the inside of the flask by the other set, is regulated and indicated by a pin, *g*, secured upon the part *b*, and a recess, *h*, formed upon the flange *b'* of the part or section *B*, forming, when the sections are connected, a slot and guide-pin. When the stoppin *g* is in the position shown in Fig. 1, the inlet-passage for air, to insure the flow of the liquid, and the passage for the liquid from the flask, are both open, and when the section *B* of the top is turned so as to bring the pin *g* to the opposite end of the slot *h* the passages are closed. A mouth-piece, *i*, is secured by a screw in the outlet-hole in the section *B*, and to a short tube, *j*, secured in the outlet-hole in the section *b*, is secured by a flexible connection a tube, *k*, reaching to within a short distance of the bottom of the flask, for the purpose of drawing up the liquid by applying the mouth to the piece *i*. The inlet-passage opening *e* is provided in this instance with a short tube, *l*.

It is obvious that my sectional top may be used without an air-inlet passage, although better with it, as the liquid can be drawn into the mouth with greater ease when air is ad-

mitted to the flask, and also that a flexible tube, or a tube having a flexible connection with a hollow stud or short tube secured in the liquid-passage, is not necessary, as a fixed tube might be substituted therefor; but I prefer a flexible or jointed tube, as such a tube is free to follow the inclination of the flask, so that when there is only a little liquid in it, and it is tilted or inclined to bring the liquid one corner of the bottom of the flask, the lower end of the tube will follow the movement of the liquid, and thus it may all be drawn from the flask.

My improved top may be applied to any kind of bottle, cask, or vessel, as well as to flasks for the pocket.

When the flask is to be placed in the pocket, by giving the pivot and set-screw *f* a slight turn, the section B can be made very hard to turn, thus preventing the liquid from leaking out of the flask by the accidental turning of

the part B, and the screw may be loosened when desired to render the turning easy.

It is obvious that by applying my apparatus to a tapering cork, one apparatus may be used with bottles having mouths of different sizes.

What I claim as my invention, and desire to secure by Letters Patent, is—

The combination of the fixed perforated section, the turning perforated section, (with or without the interposed perforated packing,) the mouth-piece, and the internal tube, combined and operating substantially as set forth.

In testimony whereof I have hereunto subscribed my name.

ARTHUR TAPPAN BECKER.
